Des. 176,489
Patented Dec. 27, 1955

176,489

BABY FEEDING DISH

Gilbert Winkler, West Englewood, N. J.

Application September 17, 1954, Serial No. 32,329

Term of patent 14 years

(Cl. D44—15)

Fig. 1.

Fig. 2.

Fig. 3.

Fig. 1 is a top plan view of a baby feeding dish embodying my new design;

Fig. 2 is a front elevational view; and

Fig. 3 is a bottom view.

I claim:

The ornamental design for a baby feeding dish, substantially as shown.
